2,153,680

DIRECTION CONTROL MECHANISM FOR
WELL DRILLING TOOLSJames H. Schumacher and Willis C. George,
Ventura, Calif.

Application January 30, 1936, Serial No. 61,575

21 Claims. (Cl. 255—1)

This invention relates to a means and method of automatically controlling the direction in which a rotary drill stem of a rotary well drilling apparatus may proceed in well drilling.

5 In recent years it has become highly desirable to be able to drill perfectly straight and vertical wells, particularly oil wells. The rotary well drilling apparatus conventionally employed in drilling oil wells is subject to the disadvantage that 10 the bit* or other drilling tool on the drill stem on encountering inclined strata or formation is apt to be deviated from the vertical. Many surveying devices have been developed to ascertain whether or not a deviation has occurred from the 15 vertical, the amount of deviation, and its direction. The difficulty with the use of such instruments usually is that they do not come into use until after deviation has occurred, at which time suitable steps are taken in an endeavor to make 20 correction and straighten up the hole.

It is an object of the present invention to provide the conventional rotary drill stem with an automatic apparatus which will automatically tend to maintain the drill stem vertical and to 25 keep it drilling in a vertical direction so that when the bit or other drilling tool encounters inclined strata or other formation which will tend to deflect the bit, lateral forces will be automatically imposed on the drill stem in opposition thereto, 30 tending to return the drill stem to its vertical position and maintain it in such position while drilling.

The invention, by a slight modification, is susceptible of being used to assist in urging the drill 35 stem to drill in an inclined direction when desired so that it may be advantageously used in whipstocking where occasion requires that the hole be drilled in an inclined direction.

Another object of the invention is to provide 40 a construction which will facilitate the drilling of straight well holes, which construction is of simple and durable design, requiring a minimum amount of attention on the part of the driller, and which is automatic in its operation.

45 With the foregoing and other objects in view, which will be made manifest in the following detailed description, and specifically pointed out in the appended claims, reference is had to the accompanying drawings for an illustrative embodiment of the invention, wherein:

50 Fig. 1 is a view in side elevation, parts being broken away and shown in vertical section, of the bottom of the drill stem, illustrating the invention as having been incorporated therein.

Fig. 2 is a partial view in vertical section illustrating a portion of Fig. 1 on an enlarged scale.

Fig. 3 is a partial view in vertical section illustrating another portion of Fig. 1 on an enlarged scale.

Fig. 4 is a view similar to Fig. 1, illustrating the position assumed by the construction when the drill stem has deviated from the vertical.

Fig. 5 is a view similar to Fig. 3, illustrating a portion of Fig. 4 on an enlarged scale.

Fig. 6 is a horizontal section taken upon the line 6—6 upon Fig. 4.

Fig. 7 is a horizontal section taken upon the line 7—7 upon Fig. 4.

Fig. 8 is a horizontal section taken substantially upon the line 8—8 upon Fig. 4.

Fig. 9 is a partial view in vertical section, illustrating how the invention may be incorporated in a drill stem utilizing a core barrel as the drilling tool.

Fig. 10 is a partial view in vertical section, illustrating the application of the invention to a drill stem where a reamer or milling tool is used as the drilling tool.

Fig. 11 is a partial view in vertical section, illustrating a modification of the invention making it susceptible for use in drilling inclined well holes.

Fig. 12 is a horizontal section taken substantially upon the line 12—12 upon Fig. 11.

Referring to the accompanying drawings, 30 wherein similar reference characters designate similar parts throughout, 10 designates a sub located at or near the bottom of the drill stem, which is made up of stands of rotary drill pipe, not shown, that is conventionally employed in rotary well drilling. This sub has a vertical, central passage therethrough, indicated at 11, for the passage of circulation fluid that is conventionally pumped down through the drill pipe to be discharged at or near the bit. Attached to sub 10 40 is a hollow barrel 12, in the top of which there is formed a shoulder 13 for a suitable spider 14. A spindle 15 extends through the spider and is supported on an anti-friction bearing 16 so that the spindle will be influenced a minimum amount 45 by the rotation of the drill stem during drilling. Attached to the spindle 15 there is a universal joint 17 to which is connected a pendulum 18, the bottom of which may be hollow, as indicated at 19, and provided with suitable ports 20. The 50 pendulum may be made up of two parts to enable the application and attachment of suitable sealing rings 21, which may be formed of rubber or other yieldable material suitable for forming a seal. The diameter of the pendulum and of 55

the sealing rings 21 is such that the pendulum may swing within limits in barrel 12. The bit 22, shown as attached to the bottom of the barrel, may be of any preferred construction and the particular type of bit employed forms no part of the present invention. However, as shown on the drawings, in accordance with conventional practice in bits used on a rotary drill stem, the bit is provided with circulation ports 23 for the discharge of the circulation fluid which is forced downwardly through barrel 12 around the pendulum. The barrel is provided with a plurality of circumferentially spaced discharge ports arranged to discharge circulation fluid in a lateral direction and on opposite sides of the barrel in opposition to each other. These ports may be cored or otherwise formed in the walls of the barrel. While they are shown as being merely two in number, there may be more.

20 As illustrated, there are vertical passages 24 and 25, the upper ends of which terminate on the interior of barrel 12 opposite sealing rings 21. The lower ends of the passages terminate on the exterior of the barrel on diametrically opposite sides and may be divided as indicated at 26 (see Fig. 8).

Referring to Figs. 1 to 5, inclusive, the operation of the foregoing described construction may be described as follows:

30 When the drill stem is perfectly vertical, the pendulum 18 will hang centrally of barrel 12, in which case the entrances to passages 24 and 25 are both open. The circulation fluid which is pumped down through the drill stem under considerable pressure discharges through both passages 24 and 25 as well as through the ports 23 in the bit. The outwardly directed discharges of the circulation fluid through the lower ends of passages 24 and 25 will develop reactionary forces in the barrel, but as these passages have their lower ends oppositely directed the reactionary forces developed in the barrel under these conditions neutralizes. Consequently, there is no tendency under these conditions to disturb the drill stem from continuing to drill vertically downward.

40 In the event that the bit encounters an inclined strata or other formation condition which will tend to deviate the drill stem from the vertical, such deviation, as soon as it becomes sufficient, will cause the pendulum to engage the side of the interior of barrel 12 as shown in Fig. 4.

As shown in this figure, the drill stem has started to deviate toward the left with the result 55 that the pendulum has swung against the right hand side of the interior of the barrel. In this position the entrance to passage 24 is closed by the sealing rings 21 with the result that no circulation fluid discharges through passage 24.

60 Passage 25, however, is left open and circulation fluid continues to discharge therethrough. The reactionary forces developed by the discharging circulation fluid through passage 24 being no longer neutralized by the reactionary forces created 65 by the fluid discharging through passage 24, become effective to urge barrel 12 toward the right, that is, to return it to the vertical position from which it has deviated. It will, of course, be appreciated that during drilling, the 70 drill pipe and, consequently, barrel 12 are continuously rotating. The entrance to passage 24 is only closed during those instants of time when barrel 12 is in the position shown in Fig. 4 during the rotation. In other words, at a given instant of time the construction will have the posi-

tion shown in Fig. 4, but as rotation continues, the entrance to passage 24 will pass from engagement with the sealing rings 21. When the barrel has rotated 90° from the position shown in Fig. 4, both passages 24 and 25 are open so that the 5 reactionary forces created by the discharging circulation fluid through both of these ports in this position are neutralized and there is no tendency to urge the drill stem either forward or backward. When, however, the barrel 12, in the course of 10 rotation, has rotated 180° from the position shown in Fig. 4, passage 25 assumes the position of passage 24, as shown in Fig. 4, so that its entrance is closed by the sealing rings on the pendulum. Passage 24, which then assumes the position 15 shown for passage 25, remains open, and the reactionary forces developed by the discharging circulation fluid therethrough not being neutralized they are also effective to urge the drill stem from left to right so as to return it to the vertical. 20

It will thus be appreciated that in this construction the entrances to passages 24 and 25 are consecutively closed by the pendulum during rotation, leaving the opposed ports open, which are directed in the direction of deviation of the drill 25 stem so that reactionary forces which will not be neutralized will be effective to urge the drill stem to return to vertical.

30 It will be appreciated, also, that the construction is entirely automatic and is independent in its operation of any direction in which the drill stem may be deviated from the vertical. In all instants, regardless of the direction of the direction of deviation, the construction will automatically cause reactionary forces to be developed 35 in the drill stem, tending to return it to vertical, and these become immediately operative as soon as the deviation has been sufficient to cause the pendulum to engage the side of barrel 12.

40 The construction is in no way limited in its application to rotary drill stems and may be employed regardless of the nature of the drilling tool. In Fig. 9 we have illustrated, somewhat schematically, the manner in which the invention may be employed where the drilling tool consists of a core barrel. In this form of construction the pendulum is illustrated at 40, having sealing rings 41 adapted to close the entrances to passages or ports 42 and 43, consecutively, which are formed in the walls of barrel 44, on which the core bit 45 is mounted. 46 indicates any preferred form of core barrel that may be used in conjunction with the core bit. In the type of construction it will be appreciated that if the drill stem deviates from the vertical the pendulum becomes operative, to consecutively close the ports during the rotation so as to cause resulting reactionary forces to be effective in a direction tending to return the drill stem to vertical. 50 60

65 In Fig. 10 the invention is illustrated as having been incorporated in a drill stem using a reamer or a milling tool as the drilling tool. In this construction the pendulum is indicated at 50, having the sealing rings 51, and disposed within barrel 52. The reamer or milling tool is indicated at 53 and the passages which are adapted to be consecutively closed by the pendulum are illustrated at 54 and 55. The operation and advantages in this form of construction are the same 70 as those previously described.

75 In Fig. 11 a modified form of the invention is disclosed, which can be advantageously used in drilling inclined holes or in whipstocking. In this form of construction the barrel is indicated 75

at 60, within which is disposed the pendulum 61 carrying the sealing rings 62. The passages formed in the walls of barrel 60 are vertical as shown in the previously described figures. One 5 passage, indicated at 63, has its entrance 64 adapted to be closed by sealing ring 62 on one side of the barrel. The exit from passage 63 is on the opposite side of the barrel, as indicated at 65. Similarly, the entrance 66 of passage 67 is dia- 10 metrically opposite entrance 64 but the exit from this passage is on the opposite side of the barrel, as indicated at 68, and is diametrically opposite exit 65. In using this type of construction, when it is desired to drill an inclined hole some divert- 15 ing means, such as a whipstock, is used to initially deflect the bit in the desired direction. This causes the pendulum 61 to swing against one side of the barrel. However, in this form of construction, wherein the passages extend circumferentially around the barrel, the effect is to have the discharging circulation fluid through the open passage create reactionary forces on the drill stem in the same direction as that in which the drill stem has been deflected. In other words, 20 in this form of construction, the reactionary forces created by the issuing streams of circulation fluid, instead of being effective in directions in opposition to deviation from the vertical, are effective in the same direction as that in which the drill stem has been deflected. This construction, 25 therefore, serves to maintain the drill stem deflected in the direction in which it may have been started by some instrument such as, for example, a whipstock.

30 It will be appreciated from the foregoing that we have disclosed a method and apparatus for controlling the direction of the drill stem of the conventional rotary well drilling apparatus. The construction is automatic in its operation and of 40 simple and durable design, requiring a minimum amount of attention. Furthermore, it becomes immediately effective to return the drill stem to its vertical position as soon as material deflection or deviation has occurred, thus making correction 45 at the very start of the deviation rather than postponing correction until after the well may have seriously diverted from the vertical and have been laboriously surveyed.

Various changes may be made in the details 50 of construction without departing from the spirit or scope of the invention as defined by the appended claims.

We claim:

1. In combination with a rotary drill stem, 55 means associated with the drill stem and located near the bottom thereof operable by a deviation of the drill stem from the vertical for causing a force to be exerted laterally upon the drill stem in a direction opposite to that in which the drill 60 stem tends to deviate from the vertical.

2. In combination with a rotary drill stem through which circulation fluid is adapted to be discharged, means associated with the drill stem near the bottom thereof operable by a deviation 65 of the drill stem from the vertical for causing the circulation fluid to be discharged in such direction as the drill stem tends to deviate from the vertical so that reactionary forces developed upon the drill stem by the discharging circulation fluid 70 will tend to maintain the drill stem vertical.

3. In combination with a rotary drill stem through which circulation fluid is adapted to be discharged, means associated with the drill stem near the bottom thereof for causing the circulation fluid to be discharged in greater amount in 75

such direction as the drill stem tends to deviate from the vertical than in other directions so that reactionary forces developed upon the drill stem by the discharging circulation fluid will tend to maintain the drill stem vertical. 5

4. In combination with a rotary drill stem through which circulation fluid is adapted to be discharged during rotary drilling, means providing laterally directed ports through which the circulation fluid may be discharged, and 10 means operable to close the ports against the discharge only when they are directed in directions opposite to that in which the drill stem tends to deviate from the vertical whereby when the ports are directed in the direction of deviation 15 of the drill stem the discharging fluid therethrough will set up reactionary forces in the drill stem tending to return the drill stem to the vertical. 20

5. In combination with a rotary drill stem 25 through which circulation fluid is adapted to be discharged, means providing circumferentially spaced, laterally directed discharge ports in the drill stem near the bottom of thereof, a pendulum mounted for universal swinging movement in the drill pipe, and closure means carried by the pendulum for closing consecutively the ports as they pass during rotation of the drill stem on that side of the drill stem against which the pendulum may swing. 30

6. In combination with a rotary drill stem through which circulation fluid is adapted to be discharged, means providing circumferentially spaced, laterally directed discharge ports in the drill stem near the bottom thereof, a spider in the drill stem, a spindle rotatably mounted in the spider, an anti-friction bearing for the spindle, a universal joint connected to the spindle, a pendulum suspended from the universal joint for swinging movement in the drill stem, and closure 35 means carried by the pendulum for consecutively closing the ports as they pass during rotation of the drill stem on that side of the drill stem against which the pendulum may swing. 40

7. In combination with a rotary drill stem, 45 means tending to assume a predetermined position with respect to the vertical independently of positions assumed by the drill stem during drilling, and means affected by said means for causing lateral forces to be developed upon the 50 drill stem when the drill stem deviates from a predetermined drilling direction, which lateral forces are in such a direction as to tend to return the drill stem to the predetermined drilling direction. 55

8. In combination with a rotary drill stem, means in the drill stem adjacent the bottom thereof tending to normally assume a predetermined position with respect to the vertical independently of the position assumed by the 60 drill stem, and means affected by said means for causing unbalanced lateral forces to be developed upon the drill stem when the drill stem deviates from a predetermined drilling direction, which lateral forces are in opposition to the direction 65 of deviation.

9. In combination with a rotary drill stem from which circulation fluid is adapted to be discharged, circumferentially spaced discharge ports for discharge of circulation fluid, means associated with the drill stem near the bottom thereof tending to normally assume a predetermined position with respect to the vertical independently of the drill stem, and means movable by said means for varying the flow through the ports dur- 70 75

ing rotation of the drill stem when the drill stem deviates from a predetermined drilling direction so as to cause unbalanced reactive forces to be developed upon the drill stem in opposition to 5 the direction of deviation and thereby tend to return the drill stem to the predetermined drilling direction.

10. In combination with a rotary drill stem, means associated with the drill stem near a drilling tool thereon adapted to normally assume a predetermined position independently of the position of the drill stem, and means operable thereby for causing circulation fluid to be discharged equally upon opposite sides of the drill stem so 15 that reactive forces developed therefrom will be substantially balanced as long as the drill stem continues in a predetermined drilling direction and to cause the circulation fluid to be discharged to a greater extent in such direction as the drill 20 stem may tend to deviate from the predetermined direction and thereby create unbalanced reactive forces on the drill stem in a direction tending to return it to the predetermined drilling direction.

11. In combination with a rotary drill stem, 25 laterally directed circumferentially spaced discharge ports in the drill stem, and means for causing circulation fluid to discharge equally through all ports so that reactionary forces developed on the drill stem will balance when the 30 drill stem is proceeding in a predetermined drilling direction and for causing the discharge through all ports to change during rotation of the drill stem when the drill stem deviates from the predetermined drilling direction so as to produce 35 unbalanced reactionary forces upon the drill stem tending to return it to the predetermined direction.

12. In combination with a rotary drill stem, 40 means for causing circulation fluid to be discharged from circumferentially spaced discharge ports so as to create balanced reactionary forces on the drill stem when the drill stem is in a predetermined drilling position, and means for causing the circulation fluid to be discharged from 45 said ports in such a manner as to create unbalanced reactionary forces in opposition to the direction of deviation when the drill stem deviates from said predetermined drilling position whereby the unbalanced forces may tend to return the drill stem to said predetermined position.

13. In combination with a rotary drill stem, 50 means for causing circulation fluid to be discharged from circumferentially spaced discharge ports so as to create balanced reactionary forces 55 on the drill stem when the drill stem is in a vertical drilling position, and means operable by the drill stem deviating from a vertical drilling position for causing the circulation fluid to be discharged from said ports in such a manner as to 60 create unbalanced reactionary forces in opposition to the direction of deviation when the drill stem deviates from the vertical whereby the unbalanced forces may tend to return the drill stem to vertical drilling position.

14. In combination with a rotary drill stem, 65 means associated with the drill stem near a drilling tool thereon adapted to assume a predetermined normal position with respect to the vertical independently of the position of the drill stem, 70 and means operable thereby for causing forces to be imposed laterally upon the drill stem in opposition to such direction as the drill stem may tend to deviate from a predetermined drilling direction to cause it to return to said predetermined 75 drilling direction.

15. In combination with a rotary drill stem, means associated with the drill stem near a drilling tool thereon adapted to assume a predetermined normal position with respect to the vertical independently of the position of the drill stem, 5 and means operable thereby for causing forces to be imposed laterally upon the drill stem in opposition to such direction as the drill stem may tend to deviate from a predetermined drilling direction to cause it to return to said predetermined 10 drilling direction and to discontinue being imposed on the drill stem upon its returning to substantially the predetermined drilling direction.

16. In combination with a rotary drill stem, 15 means causing laterally directed unbalanced forces to be imposed upon the drill stem near the bottom thereof in opposition to the direction in which the drill stem deviates from a predetermined drilling direction, and means associated 20 with the drill stem tending to assume a normal predetermined position with respect to the vertical irrespective of deviations of the drill stem for causing said means to become operative upon the drill stem deviating from the predetermined 25 drilling direction.

17. In combination with a rotary drill stem, 30 means causing laterally directed unbalanced forces to be imposed upon the drill stem near the bottom thereof in opposition to the direction in which the drill stem deviates from a predetermined drilling direction, and means associated 35 with the drill stem tending to assume a normal predetermined position with respect to the vertical irrespective of deviations of the drill stem for causing said means to become operative upon the drill stem deviating from the predetermined drilling direction and to discontinue operation upon the drill stem returning to the predetermined 40 drilling direction.

18. In combination with a rotary drill stem, 45 means for causing laterally directed unbalanced forces to be imposed upon the drill stem near the bottom thereof in opposition to the direction in which the drill stem deviates from the vertical, 50 and means associated with the drill stem tending to assume a normal predetermined position with respect to the vertical irrespective of deviations of the drill stem for causing said means to become operative only upon the drill stem deviating 55 from the vertical.

19. In combination with a rotary drill stem, 60 means for causing laterally directed unbalanced forces to be imposed upon the drill stem near the bottom thereof in opposition to the direction in which the drill stem deviates from the vertical, 65 and means associated with the drill stem tending to assume a normal predetermined position with respect to the vertical irrespective of deviations of the drill stem for causing said means to become operative only upon the drill stem deviating from the vertical, and to discontinue operation upon the drill stem returning to the vertical.

20. In combination with a rotary drill stem, 70 means for causing laterally directed unbalanced forces to be imposed upon the drill stem near the bottom thereof in opposition to the direction in which the drill stem deviates from a predetermined drilling direction, and pendulum means 75 associated with the drill stem tending to assume a normal predetermined position irrespective of deviations of the drill stem for causing said means to become operative only upon the drill stem deviating from the predetermined drilling direction.

21. In combination with a rotary drill stem, means for causing laterally directed unbalanced forces to be imposed upon the drill stem near the bottom thereof in opposition to the direction in which the drill stem deviates from a predetermined drilling direction, and pendulum means associated with the drill stem tending to assume a normal predetermined position irrespective of

deviations of the drill stem for causing said means to become operative only upon the drill stem deviating from the predetermined drilling direction and to discontinue operation upon the drill stem returning to the predetermined drilling direction. 5
